UNITED STATES PATENT OFFICE.

ALWIN RAMSEY, OF DANVILLE, ILLINOIS.

CAR COUPLER.

Application filed September 4, 1924. Serial No. 735,868.

To all whom it may concern:

Be it known that I, ALWIN RAMSEY, a citizen of the United States, and a resident of Danville, in the county of Vermilion and 5 State of Illinois, have invented certain new and useful Improvements in Car Couplers, of which the following is a specification.

My invention relates to devices of the above mentioned character, adapted to couple cars of the industrial type and has for 10 its principal object to afford a quick and safe means of operation.

A further object of my invention is to provide a car coupler so constructed whereby 15 the coupling link may not be caught between two cars and bent and so constructed that the coupling links may not be caught between the bumpers of the cars thereby preventing the necessity of moving the cars to 20 disengage said link.

A still further object of my invention is to provide a car coupler whereon the coupling links are always held in such position that they may be picked up on moving cars without 25 placing the hand in danger of being caught and injured between parts of two cars.

Other objects and advantages will be apparent during the course of the following 30 description.

In the drawing, which forms a part of this specification and in which only a preferred embodiment of my invention is shown,

35 Figure 1 is a plan view of a pair of couplers attached to the ends or draw bars of industrial cars;

Fig. 2 is a side elevation thereof;

40 Fig. 3 is a side elevation of a modified form of my invention showing the coupling link extended;

Fig. 4 is a bottom plan view of a still further modified form of my device; and

45 Fig. 5 is a sectional view on the line 5—5 of Fig. 4.

Referring in detail to the drawing, in which like characters of reference are employed to designate like parts throughout the same, the numeral 6 designates the draw head, which is provided with a rearwardly 50 extending horizontal shank 7. The front of the draw head 6 is provided with an upwardly cast integral therewith and disposed below the hook 8 is a downwardly

projecting hook 9, the lower extremity of 55 which is flanged at 9'. The draw head 6 is fastened by means of bolts 10 passing through the flanged portion 9' of the lower hook 9 to the draw bar 11 of a car 12.

An elongated link 13 is passed under the 60 portion 7 of the draw head 6, encircling the hook 8. The link 13 is adapted to travel in a horizontal plane in a space 14, between the position 7 and the surface of the draw bar 11. The lower hook 9 limits the forward 65 movement of the hook 13. It may be seen from Figs. 2 and 3 of the drawings that the upper face 15 of the flange 9 and the portion 7 will prevent the link 13 from falling below a horizontal position, but it may be 70 raised to any angle above the horizontal.

Fig. 3 shows a modified form of my device wherein the rear extremity of the portion 7 is formed into a boss 16, through which a bolt 17 is passed, bolting it to the 75 draw bar 11 of the car 12. This form of the coupler is for the purpose of heavy duty.

Fig. 4 shows a form of device adaptable to the bottom of a car body 12' provided 80 with bumpers 18. The draw head 6 consists of a shank 7, the front end of which, forms an upstanding hook 8 and a downwardly projecting lug 9. The rear end of the shank 7 forms a downwardly projecting lug or boss 85 19. A triangular shaped plate 20 is attached to the bottom of the draw head, the apex of the triangle at the lug 19, by bolts 21. A pair of ears 22, laterally disposed to the shank 7, intermediate its ends, are adapted 90 to fasten the draw head of the car body, as shown in Figs. 4 and 5. The link 13 is held in the space 23 formed between the shank 7 and the plate 20.

In the operation of my device, one end of 95 the link 13 of a draw head 6 is hooked over the hook 8 of the draw head of an adjoining car, as shown in Figs. 1 and 2. It may be clearly seen that the elongated formation of the links and hooks will limit the lateral 100 movement of the links to a degree necessary to operation, and guide it in a longitudinal path rearward to a position where it will not interfere with parts of the car, while the vertical movement of the links is limited, as 105 heretofore described. With these limits on the movement of the links, it is impossible for them to become engaged with parts of

the car thus becoming broken or bent. It may also be seen, by referring to these figures, that the link may be grasped either to engage or disengage it without subjecting 5 the hand to danger of injury between parts of the car.

It must be understood that the shape of the draw heads or the length of the links or the arrangement or strength of the links 10 must be adapted to the use they are subjected and that any changes in these may be resorted to without departing from the spirit or scope of the subjoined claim.

Having thus described my invention, what I claim is:

In combination with a car coupler of a draw head, a pair of oppositely disposed vertical hooks; a horizontal, rearwardly projecting shank intermediate said hooks, an elongated link slidably and pivotally mounted beneath said shank, a flanged base on said draw head whereby the draw head is fastened to a car, said flanged base and said shank adapted to limit the downward vertical movement of said link.

ALWIN RAMSEY.
